UNITED STATES PATENT OFFICE.

MAX GARBELL, OF CHICAGO, ILLINOIS, ASSIGNOR TO GARBELL TYPEWRITER CORPORATION, OF CHICAGO, ILLINOIS, A CORPORATION OF ILLINOIS.

COMBINED PAPER FEED AND FINGER RELEASING MECHANISM FOR TYPEWRITERS.

1,374,399.

Specification of Letters Patent. Patented Apr. 19, 1921.

Application filed December 26, 1919, Serial No. 347,477. Renewed February 24, 1921. Serial No. 447,556.

To all whom it may concern:

Be it known that I, MAX GARBELL, a citizen of the United States, residing at Chicago, in the county of Cook and State of Illinois, have invented certain new and useful Improvements in Combined Paper Feed and Finger Releasing Mechanism for Typewriters, of which the following is a specification.

10 The invention relates to improvements in that part of a typewriter employed for the insertion, feeding, guiding and holding sheets of paper in the proper positions, and it consists in certain peculiarities of the construction, novel arrangement, combination and operation of the various parts thereof, as will be hereinafter more fully set forth and specifically claimed.

20 The principal object of the invention is to provide a simple, durable, convenient and efficient mechanism whereby the paper holding fingers will be automatically released simultaneously with the release of the paper feed by the same instrumentalities and operation.

25 Another important object is to provide means for automatically locking or holding said fingers in their released positions or away from the platen until it is desired to return the paper feed and fingers to their normal or operative positions.

30 Other objects and advantages of the invention will be disclosed in the following description and explanation.

35 In the accompanying drawings, which serve to illustrate an embodiment of the invention—

40 Figure 1 is a plan view of a portion of the carriage frame of a typewriter showing my improvements mounted thereon and illustrating the platen and paper table or platform shortened for the convenience of illustration.

45 Fig. 2 is a transverse sectional view taken on line 2—2 of Fig. 1 looking in the direction indicated by the arrows showing the parts of the mechanism in about their normal or operative positions.

50 Fig. 3 is a similar view of like parts showing the paper feed and paper holding fingers in their released positions.

55 Fig. 4 is a view partly in elevation and partly in section taken on line 4—4 of Fig. 1 looking in the direction indicated by the arrows showing certain details of the con-

struction of the mechanism in their normal or operative positions.

Fig. 5 is a similar view of like parts showing them in a different position.

Fig. 6 is a detached perspective view of 60 the lever which operates the paper holding means.

Fig. 7 is a detached perspective view of the main or operating lever of the device looking toward the inner surface thereof, 65 and

Fig. 8 is a similar view of said lever looking toward the outer surface thereof.

Like numerals of reference refer to corresponding parts throughout the different 70 views of the drawings.

The numerals 10 and 11 designate portions of the end pieces or plates of the carriage of the machine which plates may be connected together by means of bars or rods 12 in 75 the ordinary or any well known way and have journaled thereon a shaft 13 on which is mounted between the end pieces or plates 10 and 11 a platen 14 and on its outer ends knobs 15 by means of which the platen can 80 be rotated when desired.

The carriage frame is supported by suitable carriage rail supports 16 which are located beneath said frame at proper distances apart and extended transversely with respect to the end pieces or plates 10 and 11 and each of said supports is provided on its upper end with a pair of prongs 17 as is clearly shown in Figs. 2 and 3 of the drawings. Between the prongs 17 of each 90 support 16 is located a race member consisting of a pair of rails 18 and 19 located side by side and angular in cross-section at their upper portions. These rails provide at their upper portion a race or holder for anti-friction balls 20 on which the carriage rails 21 rest which rails are also angular in cross-section as is clearly shown in Figs. 2 and 3 of the drawings. Each of the carriage rails 21 has on its outer portion a laterally extended 95 flange 22 to rest under and engage an inwardly extended and over-hanging flange 23 with which each member 18 of the races is provided.

The carriage rails 21 may be secured to 105 the bars or rods 12 and to the end plates 10 and 11 of the carriage in any suitable or well known way.

By reference to Fig. 1 of the drawings, it will be seen and understood that the end 110

plates or pieces 10 and 11 of the carriage frame are connected together by means of rocker bars 24 and 25 which are by preference angular in cross-section except at their 5 ends which are cylindrical in order to fit in correspondingly shaped openings in the end pieces 10 and 11 to permit of rocking movement of said bars.

At one end of each of said bars a spring 10 26 having one of its ends secured thereto and its other end secured to the end plate adjacent thereto surrounds the same to actuate said bars in one direction. One of the 15 end plates or pieces, usually the one at the right of the machine indicated by the numeral 11, is provided with a horizontally extended arm 27 which has on its inner lower portion a horizontally and inwardly extended ledge or member 28 used for a 20 stop for the main or operating lever of the mechanism and also as a finger rest for the operator.

Mounted on the shaft or bar 24 so as to turn therewith is a paper table or platform 25 29 which is by preference made of sheet metal and substantially S-shaped in cross-section as is shown. This table or platform constitutes a part of the paper feed and extends somewhat above and rearwardly of 30 the bar 24 on which it is mounted and also extends downwardly and forwardly and then upwardly near the platen as will be readily understood by reference to Figs. 2 and 3 of the drawings.

35 The table 29 is provided in its front lower portion at a suitable distance from each of its ends with a pair of downwardly extended ears 30 which are by preference punched out of the material of which the table is 40 made, thus leaving an opening between the members of each pair of ears for the reception of a portion of a rubber or rubber tired roller 31, one of which is journaled between each of the pairs of ears and extends 45 through the openings in the table a slight distance so as to contact with the paper and to hold it against the platen when the parts are in the positions shown in Fig. 2 of the drawings.

50 Mounted on one end of the rocker shaft or bar 24 is a main or operating lever 32 which extends forwardly along the inner surface of the end piece 11 and terminates at its free end near the free end of the arm 55 27. This lever is provided at its inner end by suitably fashioning said end portion, with an angular opening 33 to receive the angular part of the shaft or bar 24, and on its outer surface at said end with a circular 60 opening 34 to receive the cylindrical part or journal at one end of said shaft. The opening 34 of the lever 32 is formed in a down-turned flange 35 on said lever, and by this arrangement it is obvious that as the lever 65 32 is located on the shaft 24 adjacent to the

end plate 11 the angular opening of said lever will prevent the same turning on said shaft while the circular opening will surround the cylindrical part of said shaft and abut against the end of the angular 70 portion, thus preventing sliding or displacement of the lever on said shaft.

It will be observed in Figs. 7 and 8 that the flange 35 of the lever 32 has at its inner end a shoulder 36 and below said shoulder 75 a cam or inclined edge 37 which construction will position the front portion of the lever at a slight distance from the end piece 11 for the reception and operation of the longer arm 38 of a bell crank lever mounted 80 on the shaft 25 near one of its ends, and used for operating the paper holding fingers or means. This bell crank lever is provided in its upper portion with an angular opening 39 to receive the angular part of the 85 rocker shaft 25 near its end which is journaled in the end piece 11 of the carriage frame, and has a shorter arm 40 provided with an inwardly extended ledge or finger rest 41 for tripping said lever when desired.

Mounted on the rocker bar 25, and by preference for longitudinal adjustment thereon, is a pair of paper holding fingers 42 which may be of any suitable material, 95 but by preference of flexible material. As shown, these fingers are substantially segmental in shape and each of them has near its free end a pair of outwardly extended ears or brackets 43 between each pair of 100 which is journaled a rubber or rubber tired roller 44 to press and hold the paper against the platen in the operation of the machine. The ears 43 are by preference punched out of the front portions of the fingers 42 thus 105 providing an opening 45 in each of said fingers through which portions of said rollers will extend to contact with the paper or platen.

The rocker shaft 25, fingers 42, and rollers 110 44 constitute a form of the paper holding means which I have found efficient, but which construction may be varied without departing from the spirit of the invention.

By reference to Figs. 4 to 6 inclusive, it 115 will be observed that the longer arm 38 of the lever which operates the rocker bar 25 of the paper holding means is provided near its lower end and on its rear edge with a downwardly inclined projection 46 which 120 terminates with an abrupt shoulder 47 to engage the upper surface of the flange 35 of the lever 32 when the paper feed means is released to lock the paper holding fingers or means in released position as is clearly 125 shown in Fig. 3 of the drawings. The inclined or cam face of the part 46 of the arm 38 of the bell crank lever is for engagement with the inclined or cam shaped edge 37 of the flange 35 on the main or operating 130

lever as shown in Figs. 2 and 4 of the drawings for holding the paper feed and the paper holding means in their operative positions as is clearly illustrated in Fig. 2 of the drawings.

From the foregoing, and by reference to the drawings, it will be readily understood and clearly seen, that assuming that the parts are in the positions shown in Figs. 1 and 2 and it is desired to insert paper between the table 29 and the platen 14, the main or operating lever 32 can be depressed at its outer end by placing the thumb or finger thereon with pressure, which operation will cause the rocker bar 24 to rock forwardly at its upper portion against the tension of the springs 26 thereon.

In this movement it is obvious that the paper table 29 will be moved at its lower portion from the platen and as the inclined or cam edge 37 of the flange 35 on the operating lever slidingly contacts with the inclined or cam part 46 of the longer arm 38 of the bell crank lever which operates the paper holding means, said paper holding means or fingers will be moved upwardly from the platen, thus permitting paper to be inserted between the paper feeding means, the paper holding means and platen and properly adjusted, when by removing the pressure from the operating lever 32 the parts will assume their normal or operative positions as shown in Fig. 2 of the drawings, thus clamping the paper against the platen so that it can be moved as required by turning the platen in the proper direction.

The foregoing operation will be performed by continuous pressure on the outer end of the main or operating lever, but if it is desired to automatically lock the paper holding means in its released position when the paper feed is in its released position as shown in Fig. 3 of the drawings, all that is necessary is to depress the lever 32 far enough to cause the shoulder 36 of said lever to engage the shoulder or notch 47 of the arm 38, on the lever which operates the paper holding fingers, in which positions the parts will be held until the arm 38 of the bell crank lever is released from the main or operating lever, which may be done by applying pressure to the arm 40 of said bell crank lever, which operation it is manifest will disengage the projection 46 from the flange 35 of the main lever and permit the springs 26 to return the parts to their normal positions.

By my improvements it is evident that the paper can be readily and suitably adjusted without danger of producing carbon marks while straightening it and that both hands of the operator will be free to manipulate the paper as desired.

It will be further understood that by means of the mechanism both fingers of the

paper holder will be released from the platen at the same time by the same operation, and by means of the same parts and operation that releases the paper feeding means.

Having thus fully described my invention, 70 what I claim as new and desire to secure by Letters Patent is—

1. A device of the class described, consisting of a frame, a platen rotatably mounted thereon, paper supporting and feeding 75 means mounted to swing about a common fixed axis located above the platen on said frame and extended under the platen, paper holding means pivotally mounted on the frame at a point above the platen and ex- 80 tended over the same, and means connecting the paper supporting and feeding means and the paper holding means for simultaneously actuating them from the platen.

2. A device of the class described, consisting of a frame, a platen rotatably mounted thereon, paper supporting and feeding means mounted to swing about a common fixed axis located above the platen on said frame and extended under the platen, paper holding 90 means pivotally mounted on the frame at a point above the platen and extended over the same, means connecting the paper supporting and feeding means and the paper holding means for simultaneously actuating 95 them from the platen, and means for locking said holding means in its released position when the feeding means is in its released position.

3. In a device of the class described, the 100 combination with a frame, of a platen rotatably mounted thereon, a rocker shaft journaled on the frame in parallelism with the platen, paper feeding means mounted on said shaft to turn therewith and extended 105 under the platen, an operating lever fixed at one of its ends to said shaft and extended therefrom, another rocker shaft journaled on the frame in parallelism with the platen, paper holding means mounted on the last 110 named shaft to turn therewith and extended over the platen, and a lever fixed on the last named shaft and engaging the first named lever whereby said shafts will be rocked in opposite directions by move- 115 ment of the first named lever.

4. In a device of the class described, the combination with a frame, of a platen rotatably mounted thereon, a rocker shaft journaled on said frame in parallelism with the platen, paper feeding means mounted on 120 said shaft to turn therewith and extended under the platen, another rocker shaft journaled on the frame in parallelism with the platen, paper holding means mounted on the last named shaft to turn therewith and extended over the platen, an operating lever fixed at one of its ends to the first named shaft and having a longitudinally extended 125 and downturned flange provided at its free 130

- end with an inclined surface, an arm fixed to the last named shaft and extended into the path of the inclined surface of said flange, and having an inclined surface to 5 co-act with the first named inclined surface.
5. In a device of the class described, the combination with a frame, of a platen rotatably mounted thereon, a rocker shaft journaled on said frame in parallelism with the 10 platen, paper feeding means mounted on said shaft to turn therewith and extended under the platen, another rocker shaft journaled on the frame in parallelism with the platen, paper holding means mounted on 15 the last named shaft to turn therewith and extended over the platen, an operating lever fixed at one of its ends to the first named shaft and having a longitudinally extended and downturned flange provided at its free 20 end with an inclined surface, an arm fixed to the last named shaft and extended into the path of the inclined surface of said flange, and having an inclined surface to co-act with the first named inclined surface, said 25 arm having below its inclined surface a recess to engage the free end of said flange.
6. A device of the class described, including in combination a support, a rocker shaft journaled at one of its ends therein for rock- 30 ing movement and being angular in cross-section inwardly of said journal, an operating lever mounted at one of its ends on said shaft and having at said end an angular opening to receive the angular part of 35 the shaft and provide with a downturned flange having a circular opening in register with the angular opening for the reception of the journal of said shaft, said flange being laterally offset from the body of the lever
- and terminating at its free end with a shoulder and an inclined surface leading from said shoulder, another rocker shaft journaled in said support in parallelism with the first named shaft, and an arm fixed to the last 40 named shaft and extended between the body 45 of said lever and said support and having an inclined surface to contact and co-act with the inclined surface of said flange.
7. A device of the class described, consisting of a frame, a platen rotatably mounted thereon, paper supporting and feeding means mounted to swing about a common fixed axis located above the platen on said frame and extended under the platen, paper holding means pivotally mounted on the 50 frame parallel to the first named fixed axes and extended over the platen, and means connecting the paper supporting and feeding means and the paper holding means for 55 simultaneously actuating them on the 60 platen.
8. A device of the class described, consisting of a frame, a platen rotatably mounted thereon, paper supporting and feeding means mounted to swing about a common 65 fixed axis located above the platen on said frame and extended under the platen, paper holding means pivotally mounted on the frame parallel to the first named fixed axis and extended over the platen, means con- 70 nnecting the paper supporting and feeding means and the paper holding means for simultaneously actuating them from the platen, and means for locking said holding means in its released position when the feed- 75 ing means is in its released position.

MAX GARBELL.
